UNITED STATES PATENT OFFICE

HELEN DAVIS, OF TOPEKA, KANSAS, ASSIGNOR TO THE HELEN DAVIS CAP CO., OF
TOPEKA, KANSAS, A CORPORATION OF KANSAS

MESHEDE HEADPIECE

Application filed August 16, 1928. Serial No. 300,004.

My invention relates to improvements in a meshed headpiece.

The object of my invention is to provide a headpiece coarsely woven or meshed, through which a free circulation of air to and through the hair may be had after the hair has been dressed, the headpiece having ties arranged as cords and being so positioned that engagement thereof to the headpiece will be along the extreme marginal portion of the crown body of the headpiece, by which means the binding feature of the cords will be positioned in close proximity to the peripheral edge of the crown, but arranged to avoid binding contact with the hair, except some portion that may be allowed to protrude for a specific purpose; the headpiece, being so arranged, will fit loosely over the hair, allowing it to dry without molesting the form or curl mechanically arranged; and the headpiece, being in mesh, will not materially retard the evaporation of such moisture employed in the hair treatment.

Stated in another way the invention may be said to have for its main object the production of a head gear of generally limp and elastic fabric, including a head pocket portion adapted to fit snugly over the head of the wearer forming the crown of the assembled head dress and a generally elongated streamer portion extending from an end of the head pocket portion to form the rim of the assembled head dress; the shape of the head dress, when mounted upon the head of the wearer, being maintained by the contour of the head of the wearer.

A further object of my invention is to provide a meshed headpiece made of a single piece of material, the material being loosely woven or in mesh, as stated, and being of such fabrication, the leg or tie members may be folded to a cord-like member, or may be twisted to reduce their sizes sectionally to avoid excess lapping upon the crown of the

structure; again, the leg or tie members may be applied flat and loosely about the marginal portion of the crown, but the latter way is not thought to give the best result.

A still further object of my invention is to provide a headpiece made from meshed material similar to bobbinet, the structure being arranged from a single piece of netting, rectangular in shape, with a central portion longitudinally removed, as a matter of economy and simplicity in forming the crown and ties.

These and other objects will hereinafter be more fully explained, reference being had to the accompanying drawings forming a part of this specification, wherein like characters will apply to like parts throughout the different views.

Referring to the drawings:

Fig. 1 is a plan view of the material, prior to forming the crown and the ties.

Fig. 2 is a side view, showing the crown formed, but the ties uninterrupted.

Fig. 3 is a front view, showing the gathers at the upper edge of the rectangular piece, by which means the crown is formed.

Fig. 4 is a back view of the crown, showing the preferred method of reducing the ties to a cord-like structure.

Fig. 5 illustrates the application of the meshed headpiece.

Fig. 6 is an enlarged plan or top view of the headpiece as it appears when applied as illustrated in Fig. 5, the view of the human head not being shown.

As a means to protect the hair when dressed by marcelling or otherwise, I have arranged a meshed headpiece, being made of a single rectangular piece of fabric as illustrated in Fig. 1, having a crown or head pocket portion A and a pair of generally elongated streamer or tie portions B. The said tie portions are reduced in width by removing a portion of the material therebetween, as at C, the said removed portion terminating at the

crown, as at D. The tie members, being thus reduced in width, may be folded closely together or twisted, as shown in Fig. 4.

- A crown is formed by placing the corners E together and gathering the material therebetween uniformly; and by tying said corners together or stitching the same, a rosette or button-like structure F is formed. The said rosette or button-like structure will engage 10 between the brow and the hair when the head-piece is properly placed, it being understood that the same is drawn downward toward the brow, and likewise, the marginal edge of the crown member, as shown at G in Fig. 5, and 15 on which the ties B will engage when looped, as shown in Fig. 5.

To apply the meshed headpiece, the crown portion is placed on the head, so that the peripheral edge thereof will extend below the 20 hair line at the brow, sides and back of the head; the ties are then crossed on the back and placed around to engagement paralleling the peripheral edge of the crown as nearly as possible to avoid pressing the hair snugly at 25 any point except where it is desired that a portion of the hair may extend outward, for example, as shown in Fig. 5. The free end portions of the ties are then interlapped and drawn snugly as securing means for the 30 crown in its position, where it remains until the moisture from the hair has evaporated, allowing it to remain in its dressed position without interruption. The wave of the hair, when thus protected, will remain more perfectly than if it is free and subject to undue disarrangement. Furthermore, the said 35 meshed headpiece will be a protection during hours of slumber, and may be employed for other purposes, and at all times functioning 40 as a loose enclosure for the hair, but firmly supported by reason of the tie members, which are or may be reduced to a cord-like structure to engage the peripheral edge of the head-piece, binding the peripheral portion firmly 45 to the head in close proximity to the marginal line of the hair.

Such modifications may be employed as lie within the scope of the appended claims.

Having fully described my invention, what 50 I claim as new and desire to secure by Letters Patent is:

1. A head gear formed of generally limp and elastic fabric, including a head-pocket portion adapted to fit snugly over the head of the wearer to form the crown of the assembled head dress and a generally elongated streamer portion at least approximately twice as long as the head-pocket portion and extending from an end thereof, adapted to surround the lower periphery of the head-pocket portion to form the rim of the assembled head dress; the shape of the head dress, when mounted upon the head of the wearer, being maintained by the contour of the head of the wearer.

2. A head gear comprising a generally elongated body formed of transversely elastic fabric, including a head-pocket portion and a streamer portion at least approximately twice as long as the head-pocket portion, said head-pocket portion being adapted to form the crown of the assembled head dress and said streamer portion being adapted to surround the lower periphery of said head-pocket portion to form the rim of the assembled head dress. 70

3. A head gear formed of generally limp and elastic fabric, including a head-pocket portion adapted to fit snugly over the head of the wearer to form the crown of the assembled head dress and a pair of generally elongated streamer portions at least approximately twice as long as the head-pocket portion and extending from an end thereof, adapted to surround the lower periphery of the head-pocket portion to form the rim of the assembled head dress; the shape of the head dress, when mounted upon the head of the wearer, being maintained by the contour of the head of the wearer. 80

4. A head gear comprising a generally elongated body formed of transversely elastic fabric, including a head-pocket portion and a pair of streamer portions at least approximately twice as long as the head-pocket portion, said head-pocket portion being adapted to form the crown of the assembled head dress and said streamer portions being adapted to surround the lower periphery of said head-pocket portion to form the rim of the assembled head dress. 85

5. A head gear comprising a generally elongated body formed of generally limp and transversely elastic fabric, including a head-pocket portion adapted to fit snugly over the head to form the crown of the assembled head dress, and a pair of generally elongated streamer portions at least approximately twice as long as said head-pocket portion extending therefrom, adapted to surround said head-pocket portion to form the rim of the assembled head dress when in use; the shape of the head dress, when mounted upon the head of the wearer, being maintained by the contour of the head of the wearer. 100

6. A head covering formed from a single piece of bobbinet and comprising a main body portion shaped to produce a head pocket adapted, by reason of its elasticity, to conform to the shape of the head of the wearer, and a pair of elongated tie members extending from the lower portion of said main body and adapted to surround the margin of said head pocket portion to form the rim of the assembled covering. 110

7. A turban of the character described produced from a single piece of generally elastic meshed fabric and comprising a main body portion shaped to produce a head pocket adapted, by the elasticity of the material, to 120

conform to the shape of the head of the wearer, the material below such head pocket having two relatively long and narrow streamer or tie-like portions adapted, when the head pocket portion is positioned upon the head of
5 the wearer, to be wrapped around the marginal portion of said head pocket in opposite directions and to be engaged with each other and said head pocket to secure the turban in place.

10 In testimony whereof I affix my signature.
HELEN DAVIS.
